BURIAL VAULT

Filed March 12, 1929. 2 Sheets-Sheet 2

UNITED STATES PATENT OFFICE

JOHN SCHAEFFER, OF ENID, OKLAHOMA

BURIAL VAULT

Application filed March 12, 1929. Serial No. 346,399.

The invention relates to burial vaults and has as its object to provide a device of this character which shall be moisture and insect proof, and which will last for ages.

5 The invention will be more readily understood by reference to the accompanying drawings, in which,

Fig. 1 is a perspective view showing a grave in the bottom of which is placed a concrete 10 slab or pedestal, and into which grave a rough wooden box is being lowered;

Fig. 2 is a similar view showing the wooden box placed upon the pedestal and the top of the box removed;

15 Fig. 3 is likewise a perspective view of the grave, showing a casket placed within the wooden box and the top of the box about to be replaced, and the whole covered by a metallic hood;

20 Fig. 4 is a view similar to Fig. 3, in which the hood has been lowered into position over the wooden box;

Fig. 5 is a transverse sectional view of the completed vault, showing the pedestal, 25 wooden box and hood in place, and showing a reinforcing covering of concrete, and

Fig. 6 is a detail perspective view showing a portion of the removable bottom of the wooden box and a portion of a metallic sealing member which is secured to the under side of the bottom member and which is provided with up-turned portions for improving the vermin seal.

Referring first to Fig. 1, the reference numeral 10 denotes the outline of a grave which is of such size as to receive the completed vault. In the bottom of the grave is placed a pedestal designated by the reference numeral 11, which pedestal is elongated in form 30 and extends to within a few inches of the sides and ends of the grave. This pedestal is cut away beneath, as at 12, so as to provide an air space intermediate the ends thereof, so that the pedestal will be substantially elevated above the bottom of the grave. After the pedestal is in place, a rough wooden box 13 is lowered onto the pedestal. This box is provided with a removable top 14 and a removable base 15. At the bottom of the base 50 member is a metal sheet 16 which is turned

up at its ends and sides over the bottom of the side members 18 of the wooden box, such side members being cut away as at 19 to receive these upturned portions. This construction is clearly shown in Figs. 5 and 6. The metal 55 base is provided with a plurality of very small perforations 20 about the center of the base, which are intended to permit any liquids which may accumulate within the vault to escape. The perforations 20, while permitting liquids or gases to drain from the upper chamber, and while permitting the equalizing of pressure between the upper chamber and the air spaces below the sealing member, are nevertheless so small as to render the interior 60 of the vault proof against vermin, such as ants, bugs, gophers, etc. The wooden base 15 is secured to the side members by means of screws 22, which extend through a rectangular frame member 21.

When the box has been lowered to the position shown in Fig. 2, the top 14 is removed and the screws 22 are likewise removed, so that the base 15 is no longer attached to the side members. The rough box 65 70 75 80 85 90 95 100 is now ready to receive the casket, which in Fig. 3 is represented by the numeral 23. After the casket has been set in place, the wooden top 14 of the rough box is replaced and secured. A metallic hood 24 is now placed over the rough box in the manner shown in Figs. 4 and 5. This hood is composed preferably of copper or other non-corrodible material, and is ordinarily of the same material as the metal bottom 16, over which it tightly fits. It will be noted that the lower portion 25 of the hood extends downwardly beyond the metal base 16, to the bottom of the grave, so that an air seal is formed which effectively prevents access of moisture into the interior of the vault, while at the same time any moisture within the vault may drain from the same through perforations 20. The metal base 16 forms a permanent seal against insects, vermin or the like, and being of non-corrodible material will last forever. Likewise the hood itself will never corrode, and is prevented from collapsing by the presence of the rough box at the interior thereof. The rough box 105

itself, being effectually sealed from moisture from the outside, will never rot, but will remain intact for an indefinite period. Likewise, the remains in the coffin 23 will be permanently preserved. The seams 26 of the hood member are welded, preferably with a brass weld, so that the joints are permanent and will never corrode.

The size of the grave is such that the hood 24, after being lowered into position, is spaced several inches on each side from the walls of the grave. To protect the hood against injury and to form a rigid, enduring construction, an outer casing of concrete 27 is poured around the edges, sides and top of the hood. Preferably the concrete is reinforced by means of rods 28, or other like reinforcing material, similar reinforcing material being employed in the pedestal 11. The whole is then covered with earth and the vault and contents will remain intact for ages. If for any reason it is desirable to remove the remains, this may be done by lifting the concrete casing, hood and rough box, except the bottom, bodily from the grave by means of derricks or the like. The casket 23 may then be lifted from the base 15. This is possible, due to the fact that the base had been unscrewed from the sides of the box after the box was placed upon the pedestal in the step referred to in connection with the description of Fig. 2.

The various elements of my device cooperate to form an improved article, which is practically everlasting, and which will be moisture and insect proof. The function of the pedestal is to space the casket substantially above the bottom of the grave. By the use of the metallic bottom sealing member 16, which cooperates with the metal hood 24, an effective vermin seal is formed. The air seal prevents water from reaching the interior. Even though water were to leak into the bottom of the grave, such water would only serve to increase the air pressure within the vault and to increase the effectiveness of the seal. If the base member 16 were made of any material other than copper or like non-corrodible substance, such base would deteriorate in the course of time and would permit insects, vermin and the like to enter from the bottom. Likewise the hood, if made of material other than copper or the like would deteriorate in the course of time, even though covered by the outer concrete casing, as it is well known that concrete permits some moisture to pass through. If no metal hood were employed, it is obvious that the moisture could leak through the walls of the concrete and would eventually rot away the rough wooden box 13. The function of the wooden box in the present case is not to protect the remains from moisture, this function being performed by the

metal hood, but instead to brace the hood and to prevent the same from collapsing. By the use of this bracing material, a very thin hood may be employed, thus substantially reducing the cost of the material used. Thus 70 it will be seen that all the parts of my invention cooperate with each other to form an improved whole.

What is claimed is:

1. A burial vault comprising a pedestal to be placed in the bottom of a grave, a box supported on said pedestal and adapted to receive a coffin, a perforated metal sealing member interposed between the bottom of the box and the pedestal, a metal hood removably placed over the box, tightly fitting over the sealing member and extending below the sealing member to the bottom of the grave, leaving an air space between the bottom of the grave and the sealing member, extending around and under the pedestal, and a masonry covering for said hood. 75 80 85
2. A burial vault comprising a pedestal to be placed in the bottom of a grave, a wooden box supported on said pedestal and adapted to receive a coffin, a perforated metal sealing member interposed between the bottom of the box and the pedestal, and a metal hood removably placed over the box, tightly fitting over the sealing member and 90 95 extending to the bottom of the grave.

In testimony whereof I affix my signature.

JOHN SCHAEFFER.
